UNITED STATES PATENT OFFICE.

ALBERT EDWARD JONES, OF WESTMINSTER, LONDON, ENGLAND, ASSIGNOR TO THE
WHITEHEAD TORPEDO COMPANY LIMITED, OF WESTMINSTER, ENGLAND.

LUBRICATING DEVICE.

Application filed March 20, 1924, Serial No. 700,646, and in Great Britain December 21, 1923.

This invention relates to lubricating devices for engines and machinery in general. It is well known that the viscosity of lubricating oil varies considerably at different temperatures so that a lubricating system in which oil is fed under pressure through restrictions of different sizes according to the importance of the part to be lubricated and so designed as to supply an adequate quantity of oil in hot weather to the said parts, will supply a smaller, and sometimes inadequate, quantity in cold weather. Furthermore in some cases, such as the engines of automobile torpedoes, some of the parts to be lubricated are at a lower temperature than others and there is therefore a liability of the oil passing mainly or only to those parts at the higher temperature with the result that the other parts are more or less starved of oil. Several expedients have been devised for overcoming these difficulties but without marked success and the chief object of the present invention is to provide an improved device which will supply a measured volume of oil to the part or parts to be lubricated irrespective of the viscosity of the oil or the different temperatures of the said parts, this device being of the kind comprising a rotary member moving in contact with a ported casing and having formed through it a hole in which is disposed a plunger of smaller length than that of the hole, one end of this hole being brought, by movement of the said member, opposite an oil pressure supply port to receive a charge of oil (the plunger being moved to the other end of the hole by the act of charging) and then brought, by further movement of the said member, opposite a discharge port communicating with the part to be lubricated, whereupon the charge of oil is ejected into the latter port by oil under pressure admitted to the other end of the hole and acting upon the plunger, the ejection of the charge of oil from one end of the hole thus resulting in the other end receiving a charge of oil which is then ejected through a discharge port when the former end is brought opposite a supply port.

According to the present invention we provide the casing with several pairs of diametrically opposite supply and discharge ports arranged in a common transverse plane with the hole in the rotary member. In this manner a construction is provided which gives several deliveries of oil per revolution of the

rotary member which is balanced in regard to the oil pressure so that there is no liability of the said rotary member jamming as is the case when only one pair of ports in one plane is provided.

In order that the said invention may be clearly understood and readily carried into effect, the same will now be more fully described with reference to the accompanying drawings in which—

Fig. 1 is an axial section of a constructional form of the lubricating device.

Fig. 2 is a sectional view on the line 2—2 of Fig. 1.

Fig. 3 is a sectional view on the line 3—3 of Fig. 1.

A is the aforesaid rotary member and B is the ported casing in which this member moves.

In the construction shown the said member A is in the form of a solid rotary drum having a transverse hole A¹ therethrough which receives a plunger a¹, and the casing B in which this drum rotates is formed with radial discharge ports B¹, B², B³ for the oil. Diametrically opposite the said discharge ports are the supply ports B^{1x}, B^{2x}, B^{3x} which communicate with a duct containing oil under pressure, the pressure being generated by a pump, by compressed air or by other suitable means. The discharge ports B¹, B², B³ and the supply ports B^{1x}, B^{2x}, B^{3x} are all arranged in a common transverse plane as shown. The drum A may be rotated in a clockwise direction or in an anti-clockwise direction as desired and it will be understood that during the rotation the hole A¹ comes opposite each pair of discharge and supply ports in turn so that on each stroke of the plunger effected by the entry of oil under pressure through a supply port a measured charge of oil is discharged through a discharge port; thus two measured charges of oil are delivered to each of the three discharge ports during each revolution of the drum A. The provision of the three pairs of ports results in the feeding pressure being balanced and therefore any tendency for the drum A to jam in the casing B is avoided.

The plunger has rounded ends as its movements are intended to be limited by contact with the casing B, and is made of suitable length in relation to the length of the hole so that the required quantity of oil

passes into the hole each time the latter comes opposite a supply port. If desired the ends of the plunger may be prevented from coming into contact with the casing 5 by suitable stops constituted for example by fixed pins engaging in grooves or slots in the plunger.

Having now particularly described and ascertained the nature of my said invention 10 and in what manner the same is to be performed, I declare that what I claim is:—

15 A lubricating device for delivering to the part to be lubricated a measured volume of oil irrespective of its viscosity, comprising a rotary member formed with a hole, a plunger of smaller length than that of the hole disposed in said hole, and a casing in which said rotary member moves, said casing

having a plurality of supply ports which are arranged in a common transverse plane 20 with the hole in the rotary member and through which, in certain positions of said rotary member, charges of oil under pressure enter said hole to displace the plunger, and a plurality of discharge ports which are also arranged in a common transverse plane 25 with the hole in the rotary member and each of which is arranged opposite one of the supply ports and through which, in other positions of said rotary member, the charges 30 of oil are ejected by the displacement of said plunger in the reverse direction by the entry of the charges of oil under pressure through said supply ports.

ALBERT EDWARD JONES.
